UNITED STATES PATENT OFFICE.

JAMES S. FOX, OF JACKSON, MICHIGAN.

THIRD-RAIL SUPPORT OR CHAIR.

1,008,233.

Specification of Letters Patent.

Patented July 22, 1913.

Application filed December 27, 1912. Serial No. 738,863.

To all whom it may concern:

Be it known that I, JAMES S. FOX, a subject of the King of Great Britain, residing at Jackson, in the county of Jackson and State of Michigan, have invented new and useful Improvements in Third-Rail Supports or Chairs, of which the following is a specification.

This invention relates to improvements in electric railways and has particular application to a support or chair for holding the third rail of an electric traction system in proper position relatively to the trackway.

In carrying out the present invention, it is my purpose to provide a third rail chair or support whereby the conductor rail may be held in proper position securely and effectively and which will embrace the desired features of simplicity, efficiency, durability and strength coupled with cheapness of cost in manufacture and installation.

It is also my purpose to provide a chair or support of the class described which will be constructed in such manner that the third rail will be effectively gripped and, in effect, clamped to the chair and wherein the component parts of the chair may be readily removed to facilitate repairing or renewal of such parts.

With the above and other objects in view, the invention consists in the construction, combination and arrangement of parts hereinafter set forth in and falling within the scope of the claims.

In the accompanying drawing; Figure 1 is a fragmentary top plan view of a third rail traction system equipped with my present invention. Fig. 2 is a view partly in section and partly in side elevation of one of the supports or chairs, the contact shoe or trolley carried by the car being shown as contacting with the third rail or conductor, and Fig. 3 is a transverse sectional view through one of the supports or chairs.

Referring now to the accompanying drawing in detail, the numerals 1, 1 indicate the rails of the trackway of the system over which the cars are adapted to travel, while 2 designates the supports or chairs which are suitably fastened to the road bed adjacent to the rails of the trackway and spaced apart appropriate distances to hold the third rail or conductor.

Each chair or support comprises, in the present instance, a channeled standard or upright 3 having the lower end thereof fas-

tened to an appropriate base through the medium of bolts 4 or other fastening devices and is inclined upwardly and away from the fastening devices, as at 5 and thence extended upwardly substantially vertically as at 6, while the upper or free end thereof is curved as at 7 and extended inwardly toward the rails of the trackway. A second standard 8, in the present instance, 60 channeled, has the lower end thereof extended outwardly to form a foot 9 through which is passed a bolt or the like 10 whereby the standard 8 may be suitably secured to the base. The upper end of the last-mentioned standard is curved, inwardly, that is, to say, toward the rails of the trackway and overlies the curved end 7 of the standard 3 and the curved upper extremities of the standards of all of the supports or chairs 75 are spaced apart to receive a semicircular hood or protector 11 which contacts with the adjacent surface of the curved end 7 of each standard 3 and extends the entire distance of the trackway so as to eliminate 80 the possibility of a person or object contacting with the third rail.

Disposed within the channel in the curved end 7 of each standard 3 is a clamp or flexible holder 12 curved longitudinally to conform to the shape of the end 7 and preferably constructed of material possessing yieldable or resilient qualities. This clamp or holder has the opposite ends thereof turned inwardly to form lugs 13, 13 while 90 the central portion thereof is provided with an opening 14 alining with registering openings in the curved end 7 of the standard 3, the similar end of the standard 8 and the adjacent portion of the hood 11 and 95 through these alining openings is passed a headed bolt 15 having a threaded shank carrying a nut 16. Mounted within the clamp or holder 12 and resting upon the lugs 13, 13 thereof are insulating blocks 17, 17 having the confronting faces thereof formed to provide a substantially T-shaped slot 18 designed to receive the third rail or conductor 19, the contact surface of the latter depending below the lower ends of the insulating blocks and is designed to be contacted by a shoe or trolley wheel 20 journaled upon an axle 21 carried by a trolley pole 22, the latter being suitably fastened to the trucks of a car whereby power may be conveyed to 110 the motors of the car for propelling the same and other apparatus on such car.

In practice, the nut 16 on the bolt 15 is tightened whereby the holder or clamp 12 is drawn into the channel in the curved end 7 of the standard 3. This inward movement 5 of the clamp or holder causes the end portions thereof to exert pressure on the insulating blocks 17, 17 whereby the latter effectively clamp the adjacent portion of the third rail and so hold the latter in proper 10 position.

From the foregoing description taken in connection with the accompanying drawing, the construction and manner of employing my invention will be readily apparent. It will be seen that I have provided a third rail support for electric railroads whereby the rail or conductor is effectively clamped in position, while stability is imparted to the chair incident to the lower 15 ends of the standards constituting the same being spaced apart.

While I have herein shown and described one preferred form of my invention by way of illustration, I desire to have it understood that I do not limit or confine myself 25 to the precise details of construction herein described and delineated, as modification and variation may be made within the scope of the claims and without departing from 30 the spirit of the invention.

I claim:

1. A third rail support comprising a standard provided with a curved upper end, rail receiving blocks disposed within said 35 end, and a flexible holder arranged within said end and carrying said blocks, said

holder being curved longitudinally, and means operable to draw said holder within the curved end of said standard in a vertical direction to produce a clamping action between said blocks and third rail. 40

2. A third rail support comprising a standard provided with a curved upper end, rail receiving blocks disposed within said end, a flexible holder carrying said blocks 45 and curved longitudinally, said holder being arranged within said end, and means passed through said holder and the curved end of said standard whereby the holder may be drawn into the standard to exert a 50 clamping action upon said blocks.

3. In an electric railroad, a third rail, a series of supports or chairs for said rail spaced apart, each support comprising a channeled standard provided with a curved 55 upper end extending inwardly toward the trackway, blocks of insulating material disposed within the curved end of said channeled standard and embracing said third rail, a flexible holder curved longitudinally 60 and disposed within said end and carrying said blocks, and means passed through said standard and said holder whereby the holder may be influenced to exert pressure upon said blocks to produce a clamping 65 action between the blocks and third rail.

In testimony whereof I affix my signature in presence of two witnesses.

JAMES S. FOX.
